UNITED STATES PATENT OFFICE

HENRY M. YEAGER, OF BUFFALO, NEW YORK, ASSIGNOR TO FEEDERS MANUFACTURING COMPANY, INC., OF BUFFALO, NEW YORK, A CORPORATION OF NEW YORK

CONDENSER

Application filed August 21, 1928. Serial No. 301,070.

This invention relates to a condenser which is more particularly designed for use in domestic refrigerating apparatus for condensing the vaporized refrigerant after the same has been expanded by the heat in the spaces to be cooled so that this refrigerant can be again used in liquid form for continuing the refrigerating operation.

Condensers for this purpose usually include a coil of serpentine form upon which a plurality of radiating fins are mounted so as to increase the radiation of heat in the vapors or gases to the atmosphere and hasten the operation of liquefying the gas. In order to reduce the joints in the coil as much as possible and thereby minimize the liability of leakage of the refrigerant therefrom it has been proposed to make the coil of one continuous piece of tubing which is bent and does not employ any couplings at the turns. Such construction of the coil has heretofore not permitted of economically mounting radiating fins or strips thereon by slipping the fins lengthwise on the several convolutions of the coil because these fins can not readily pass around the turns or bends of the same, thereby not only increasing the cost of manufacture but also reducing the efficiency of the condenser.

It is the object of this invention to provide a condenser in which the coil is continuous and the bends or turns connecting the several convolutions are of the same diameter or cross section as the main sections or stretches of the coil and which is provided with radiating fins or strips so constructed that the same can be slipped over the bends and onto the main sections or stretches of the coil easily, quickly and economically and provide a condenser which is strong and durable and furnishes the maximum condensing efficiency.

In the accompanying drawings:

Fig. 1 is a side elevation of a condenser embodying my invention and showing the same organized for producing a single pass of the refrigerant.

Fig. 2 is a vertical cross section of the same taken on line 2—2, Fig. 1.

Fig. 3 is a fragmentary side elevation on an enlarged scale, of the condenser corre-

sponding to Fig. 1 but showing the last radiating fin in the form in which it is slipped simultaneously over a plurality of bends and upon a plurality of main stretches of the coil.

Fig. 4 is a vertical cross section taken on line 4—4, Fig. 3.

Fig. 5 is a horizontal section taken on line 5—5, Fig. 3.

Fig. 6 is a fragmentary perspective view of the condenser shown in Figs. 1—5.

Fig. 7 is an elevation of a modified form of radiating fin or strip embodying my improvement.

Fig. 8 is a side elevation showing a condenser made in accordance with my invention, but having two passes of the coils.

Fig. 9 is a vertical cross section taken on line 9—9, Fig. 8.

Fig. 10 is a condenser organized according to my improvement and containing three passes.

Fig. 11 is a vertical cross section, taken on line 11—11, Fig. 10.

In the following description similar characters of reference indicate like parts in the several figures of the drawings.

Referring to Figures 1—6, the numeral 20 represents the parallel main stretches or sections and 21 the turns or bends which alternately connect the corresponding ends of the stretches thereby forming a coil. This coil is made continuously from a single piece of metal tubing or piping of uniform diameter or cross section to produce a coil having a plurality of convolutions which are folded relatively to one another.

The material to be condensed may be conducted into one end of this coil in any suitable manner and the condensate discharged from the opposite end thereof is delivered to any desired place.

Upon the stretches of this coil are mounted radiating means consisting preferably of a plurality of sheet metal fins 22, each having the form of a strip and provided with a plurality of transverse corrugations 23, 24 arranged alternately on opposite sides of the strip.

Each of these fins or strips is provided with a plurality of elongated openings or slots 25

for the reception of a pair of adjacent coil stretches and for permitting this fin to be passed over the turn connecting the corresponding ends of said stretches. Each of these slots, as shown in Figs. 1-6 may be formed by punching two spaced holes 26 in adjacent parts of the fin and slitting the metal from one of these holes to the other, as shown at 27 in Figs. 2 and 6, thereby forming two wings 28 on the fin between the opposing inner sides of the companion holes 26 which normally are arranged in line or in the same plane and face each other. The wings of each of these pair of holes are now turned to one side, as shown in Figs. 3, 4, and 5 so that the two holes communicate with each other and in effect form a slot, as shown in the upper part of Fig. 4.

The coil and the fins can now be assembled by slipping each fin or strip with its several slots over the turns or bends of the coil at one end thereof and then slipping this fin over the corresponding pair of coil stretches. The distance between the centers of each pair of holes is the same as the distance between the centers of the respective pair of coil stretches whereby the opposite end portions of each of these slots fit snugly around the outer halves of the respective pair of coil stretches. After each fin or strip has been thus simultaneously slipped upon a plurality of pairs of coil stretches in this manner the wings 28 on the central parts of the longitudinal edges of each slot are again bent back into alinement so that they face each other and engage with the inner halves of the opposing inner sides of the companion coil stretches.

By this means each coil stretch is engaged by each fin around its entire periphery whereby a maximum contact is formed between the coil and the fins and a highest efficiency is obtained in transferring heat from the refrigerant to the atmosphere.

The metallic contact between the coil and the fins is further increased to hold these members in place relatively to each other and also to improve the heat transference by soldering or welding the fins on the coil stretches.

When placing the fins on the coil the corrugations of the several fins or strips engage each other and these operate as spaces which form passages for the air between the fins and coil.

These corrugations which are arranged between adjacent slots extend entirely across the respective strip, as shown at 23, but those corrugations in line with the slots are formed in sections arranged on opposite sides of each of these slots, as shown at 24, in Figs. 2, 4, 5 and 6.

If it is desired to reduce the cost of manufacture the wings 28 may be omitted and each slot left open, as shown at 29 in Fig. 7, but this construction sacrifices some of the

contact between the fins and the coil stretches.

In the construction shown in Figs. 1-6 the several convolutions of a single pipe or tube arranged in the same plane so that a condenser is produced having but a single pass or condensing region.

If a condenser is required having two passes or condensing regions a single continuous pipe or tube is bent, as shown in Figs. 8 and 9, to form two vertical tiers of coil stretches 30, 31, and each stretch of one tier is connected with the corresponding end of a stretch in the other tier by a turn or bend 32 which inclines, so that the fluid will readily flow from one convolution of the coil to another. In this construction the radiating fins or strips are made similar to those in Figs. 1-6, excepting that the coil receiving slots are inclined instead of being vertical, and all of the corrugations 33 are of sectional form instead of some being sectional and others complete.

When a condenser of larger capacity is required the number of passes may be further increased. For example, in Figs. 10 and 11 is shown a construction in which three coils are arranged to form three vertical tiers of coil stretches 34, 35, 36, which are spaced laterally from each other and the stretches or convolutions of the several coils being also staggered relatively to each other.

Each coil in this particular construction is assembled with the radiating fins or strips in the manner described with reference to the single pass condenser shown in Figs. 1-6 and the same reference characters are therefore applied to corresponding parts.

In this triple pass condenser it is preferable to connect the corresponding inlet ends of the several coils by a single inlet header or manifold 38 and the corresponding outlet ends of these coils by a single outlet header or manifold 39.

Each of the forms of my invention possesses the advantage of simplicity of construction and manufacture, maximum condensing efficiency, and absence of leakage inasmuch as the fins are fitted tightly, expeditiously and economically to coils made of continuous tubing or piping.

I claim as my invention:

1. A condenser comprising a coil having a plurality of convolutions forming main stretches and turns connecting corresponding ends of said stretches, and fins mounted on said stretches and each provided with a plurality of slots, each turn of the coil passing through one of said slots and opposite ends of each slot engaging with the outer side of adjacent stretches of the coil each of said fins being provided between the ends of each of its slots with wings which are displaced in the formation of the respective slot and which are bent into line with each other and

into engagement with the opposing inner sides of the respective main stretches after the fin has been passed over the same.

2. A condenser comprising a coil having
5 a plurality of convolutions forming main stretches and turns connecting corresponding ends of said stretches, and fins mounted on said stretches and each provided with a plurality of slots, each turn of the coil passing through one of said slots and opposite ends of each slot engaging with the outer side of adjacent stretches of the coil, said fins being corrugated and the summits of adjacent corrugations engaging with each other,
10 those corrugations transversely in line with slots in the fin being formed in sections which are arranged on opposite sides of the respective slot.

In testimony whereof I hereby affix my
20 signature.

HENRY M. YEAGER.
